Inventor:

John B. Wickersham

UNITED STATES PATENT OFFICE.

JOHN B. WICKERSHAM, OF NEW YORK, N. Y.

FOUNDATION FOR PAVEMENTS.

Specification of Letters Patent No. 11,251, dated July 11, 1854.

To all whom it may concern.

Be it known that I, JOHN B. WICKERSHAM, of the city, county, and State of New York, have invented a new and useful Improvement in the Foundations of Pavements; and I do hereby declare that the following is a full, clear, and exact description of the same, reference being had to the accompanying drawings, forming part of 10 this specification, in which—

Figure 1, is a plan or top view showing a piece of pavement and its foundation. Fig. 2, is a vertical section of the same.

Similar letters of reference indicate 15 responding parts in both figures.

The nature of my invention consists in making the foundation by placing a layer of woven, or other iron work upon a bed of gravel, broken stone, or other suitable material. The paving blocks are placed above the said iron work, in the same way as upon the usual foundations, and when the paving is complete, the weight upon each block is distributed over an area much greater than 20 its own, and hence, if that portion of the bed under any one or more blocks, should be imperfect, they are prevented from working a hole in the foundation, which would extend itself in every direction, as is the 25 case when there is any imperfection in the foundations now in use.

To enable those skilled in the art to make and use my invention, I will proceed to describe its construction and operation.

30 A, is the bed upon which the foundation is placed. This may be composed of gravel, broken stone, or any other material, or mixture of materials, commonly employed for the beds of pavements, either in a wet or 35 dry state.

b, b, is the iron work, which I have represented as composed by the interlacing or weaving of iron rods, but which may, though I believe, with less advantage, be

composed by crossing bars of wrought iron, 45 and riveting them together, or may consist of perforated, or unperforated plates of wrought or cast iron. This iron fabric is made in sections, B, each of about ten feet square, for the convenience of laying down, 50 and for its removal, if at any time necessary for repairs. The size of the rods, b, b, employed, and their distances apart, or the thickness of the plates, if plates are employed, may be such as is found in practice 55 most suitable for the particular pavement for which they are required. The sections of the iron fabric are laid down upon the bed, A, and the meshes, or interstices, 60 between the rods, or in or between the plates, are filled with gravel, broken stone, or any other suitable substance commonly used in paving, and the fabric may be thinly covered with the same material.

c, c, are the blocks, or paving stones, 65 which are laid above the iron fabric in the same way as upon any other foundation. Any description of paving stones may be used, but I consider squared blocks to be the best, as they will obtain a more equal bearing.

I do not confine myself to the employment of any particular material for, or to the manner of preparing the bed, A, nor to the employment of any particular kind or form 75 of paving stone. But

What I claim as my invention, and desire to secure by Letters Patent, is—

The employment as a foundation for pavements, of a layer of woven, or interlaced, or 80 other iron work, laid upon a bed of any suitable material, substantially as herein described.

JOHN B. WICKERSHAM.
